UNITED STATES PATENT OFFICE.

JOHN WIECHMANN, OF ALBANY, NEW YORK.

FLUE-CLEANER.

932,210.

Specification of Letters Patent. Patented Aug. 24, 1909.

Application filed May 19, 1908. Serial No. 433,696.

To all whom it may concern:

Be it known that I, JOHN WIECHMANN, a citizen of the United States, and a resident of Albany, in the county of Albany and State of New York, have invented a new and Improved Flue-Cleaner, of which the following is a full, clear, and exact description.

The invention relates to boiler flue cleaners having a cutter head rotated by a turbine or a similar motor.

The object of the invention is to provide a new and improved flue cleaner arranged to thoroughly cut the scale from the inside of the flue or tube by the use of a cutter head 15 rotating with the turbine wheel, and provided with a cutter wheel mounted to rotate loosely on the end of a centrifugal swing arm, so that the center pin of the turbine wheel is relieved of undue strain and a proper cutting 20 of the cutter wheel is insured, without danger of breaking the cutter wheel or causing it to stick in the scale.

The invention consists of novel features and parts and combinations of the same, 25 which will be more fully described herein-after and then pointed out in the claims.

A practical embodiment of the invention is represented in the accompanying drawings forming a part of this specification, in which 30 similar characters of reference indicate corresponding parts in all the views.

Figure 1 is a side elevation of the improvement, parts of the turbine and the flue or tube being shown in section; Fig. 2 is a plan view of the cutter head, the cutter wheel and part of the swing arm being shown in section; Fig. 3 is a sectional side elevation of a cutter 35 head of modified form; and Fig. 4 is a side elevation of a cutter head of another modified form.

The cutter head A of the boiler flue cleaner is rotated by a turbine B of any approved construction, preferably, however, such as is shown and described in the application for 45 Letters Patent of the United States, No. 370,866, filed by me on April 29, 1907. The cutter head A is provided with a body C having an annular flange or shoulder C', from which extends centrally and rearwardly a screw C² screwing centrally into the turbine 50 wheel B' mounted to turn in the forward end of a casing B², connected at its rear end by a ball and socket joint B³ with a coupling B⁴, to which is attached a hose B⁵ connected with 55 a fluid pressure supply, such as water under pressure, to cause the fluid under pressure to

rotate the turbine wheel B' and consequently the cutter head A.

On the body C of the cutter head A is held the pivot pin D' of a swing arm D, to the forward end of which is secured by a set screw E a spindle F on which is mounted to turn the cutter wheel G adapted to cut into the scale H on the inside of a flue or tube I, as indicated in Fig. 1. The cutter wheel G is provided with a semi-spherical body G', on the peripheral face of which are integrally formed longitudinally and radially extending cutter blades G², following approximately the curvature of the outer face of the body G'.

The base of the cutter wheel G is at the end of the swing arm D and the cutter wheel is held against forward sliding on the spindle F by a head F' formed on the outer end of the spindle F. Now when the cutter head A is rotated by the action of the turbine wheel B', then the arm D swings outward by its centrifugal force, thus causing the cutter wheel G to cut into the scale H, thus breaking up the scale as the cutter head A is revolved inside of the flue or tube I. By having the cutter blades G² arranged in the manner described, the scale is gradually engaged by the outer edges of the blades G² as the cutter head A advances in the tube I, and is rotated at the same time, and consequently the scale is completely cut up and detached from the inner surface of the tube I and washed outward in advance of the flue cleaner by the discharge of the fluid under pressure leaving the turbine B.

The centrifugal action of the swing arm D and the cutter G is preferably increased by the use of a weighted arm J, provided at its forward end with a weight J' and mounted to swing at its rear end on a pivot pin J² attached to the body C of the cutter head A. The pivotal ends of the arms D and J are connected with each other by gear teeth D², J³, so that the arms D and J swing outward or inward in unison with each other. Thus the outward swinging motion of the swing arm D carrying the cutter wheel G is aided by the outwardly-swinging weighted arm to increase the centrifugal force of the cutter wheel G.

As shown in Fig. 3, the body K of the cutter head is provided with a shoulder K' and a screw thread K² for screwing in the turbine wheel B', and on the said body K is held a pivot pin L', on which the swing arm L is

fulcrumed, the swing arm being provided at its free end with a spindle N, on which the cutter wheel O is mounted to rotate freely, the cutter wheel being the same in construction as the cutter wheel G above described. On the body K is integrally formed a weighted arm P having a lug P' for engagement by a stop lug L² held on the pivotal end of the swing arm L, to limit the outward swinging motion of the swing arm L. The weighted arm P adds weight to the cutter head to increase the momentum.

In the modified form illustrated in Fig. 4, the cutter head is provided with a body Q having the shoulder Q' and the screw thread Q² screwing into the turbine wheel B', and on the said body Q is held a pivot pin R for an arm S carrying a pivot pin T' at right angles to the pivot pin R and on which the swing arm T is mounted to swing. On the free end of the swing arm T is arranged a spindle U, on which the cutter wheel V is mounted to turn, the said cutter wheel V being similar in construction to the cutter wheels G and O above mentioned. Now by the arrangement described and shown in Fig. 4, the swing arm T has a universal joint connection with the body Q, to allow free outward swinging of the swing arm T whenever the cutter head A is rotated and advanced in the tube, for cutting the scale.

The cutter head shown in Fig. 4 is more especially designed for use in flues or tubes of three inches and less in diameter, while the cutter heads shown in Figs. 1, 2 and 3 are more especially designed for use in flues or tubes of more than three inches in diameter.

The turbine wheel B' is mounted to turn on the pin B² held centrally in the casing B² of the turbine B; and by providing the cutter head A with the centrifugal counter-balancing arms J or P or the universal joint shown in Fig. 4, the said central pin B² is relieved of

undue strain, and as the cutter wheel G, O or V is mounted to rotate loosely on the free end of the corresponding swing arm D, L or T and the cutter wheel is provided with the cutting blades as described, the cutter wheel is not liable to stick in the scale H and it effectively cuts the scale, to thoroughly clean the tube or flue.

Having thus described my invention, I claim as new and desire to secure by Letters Patent:

1. A flue cleaner having a revoluble cutter head, comprising a body, a cutter arm fulcrumed on the body, a cutter wheel mounted to turn freely on the free end of the arm, and a weighted arm carried by the body, the weighted arm and the pivoted arm having members engaging with each other.

2. A flue cleaner having a revoluble cutter head, comprising a body, a cutter arm fulcrumed on the said body, a cutter wheel mounted to turn freely on the free end of the said arm, and a weighted arm pivotally mounted on the body independently of the cutter carrying arm and connected with said arm to swing in unison therewith for increasing the centrifugal force of the arm and cutter wheel.

3. A flue cleaner having a revoluble cutter head, comprising a body, a cutter arm fulcrumed on the said body, a cutter wheel mounted to turn freely on the free end of the said cutter arm, a weighted arm fulcrumed on the said body, and a gearing connecting the said cutter wheel arm and the said weighted arm with each other.

In testimony whereof I have signed my name to this specification in the presence of two subscribing witnesses.

JOHN WIECHMANN.
